UNITED STATES PATENT OFFICE

149,218

DESIGN FOR A FLY BOX

Kenneth D. Richards, Gardner, Mass.

Application July 3, 1946, Serial No. 131,287

Term of patent 14 years

(CL. D58—13)

To all whom it may concern:

Be it known that Kenneth D. Richards, a citizen of the United States, residing at Gardner, in the county of Worcester and State of Massachusetts, have invented a new, original, and ornamental Design for Fly Box, of which the following is a specification, reference being had to the accompanying drawing, forming part thereof.

Fig. 1 is a top plan view of a fly box with its cover removed, showing my new design;

Fig. 2 is a side elevational view thereof;

Fig. 3 is a top plan view with the cover in place;

Fig. 4 is a side elevational view thereof; and

Fig. 5 is an end elevational view thereof.

I claim:

The ornamental design for a fly box, as shown.

KENNETH D. RICHARDS.
